[57] CLAIM

The ornamental design for an instrument face panel, substantially as shown and described.

DESCRIPTION

FIG. 1 is a front elevational view of an instrument face panel showing the design of this invention; and

FIG. 2 is a side elevational view thereof.

The broken lines shown in FIG. 2 indicate environment and form no part of the claimed design. The rear is plain and unornamented.

FIG. 1

FIG. 2
